UNITED STATES PATENT OFFICE

MARC GRANDJEAN, OF PARIS, FRANCE

DEVICE FOR ADJUSTING THE TYPE BARS RELATIVELY TO THE UNIVERSAL BARS IN
STENOGRAPHIC MACHINES

Application filed September 11, 1928, Serial No. 305,298, and in France October 4, 1927.

The present invention relates to a device for adjusting type bars relatively to the universal bar in stenographic machines.

The invention consists in the fact that with the universal bar cooperates an articulated member bearing tightly upon every one of the key levers and one of the ends of which is cambered so as to pass under the lever and cooperate with the universal bar, the other end of the said member having portions adjacent to holes drilled in the key lever. In this way, it is possible to regulate the position of the said part in introducing into one of the holes a point by means of which a pressure is exerted upon the said portions of the said member.

An embodiment of the device according to the invention is represented, by way of example, in the accompanying drawings.

Figure 1 is a side view of that part of the machine comprising the printing members only.

Figure 2 is a plan view.

Figure 3 is a back view.

Figure 4 is a cross section along the axis of the machine.

In the embodiment which is represented, the key levers bear upon the universal bar 6 through a cushion 9, part of which is reinforced by a flanged sheet metal strip, the other part being made of india rubber lined if necessary with a plastic matter such as lead, rubber sponge, or the like.

The printing members are assembled on a block which comprises two cheeks 1 between which are arranged partitions 2 maintained by cross ties 3.

The key levers 4 which rock about a shaft 8 are guided between said partitions and rest on a universal bar 6 through members 5.

Said members are fulcrumed tightly on levers 4 by means of riveted pins 7. One of the ends 5a is cambered so as to pass under the lever 4 and cooperate with the universal bar 6. The other end is divided into two

branches or arms 5b and 5c so arranged as to partially cover two holes 4a and 4b provided in the levers 4.

In order to regulate the position of the member 5, a point is introduced into the one or the other of the holes 4a and 4b and a lever action is exerted so as to cause the member 5 to rotate in the one or in the other direction whether it is desired to have the cambered end 5a move up or down.

It is by this means possible to regulate accurately the moment at which the said levers 4 come in contact with the universal bar 6.

The support of the key levers upon the bar 6 is effected through the medium of a cushion 9 composed of a tube or a strip of rubber 9a compressed along its length over a portion of its width in a frame of hard material 9b and maintained in this position by a rigid core 9c, whilst the other portion is empty or preferably provided inside with plastic material 9d.

The rear part of the bar 6 is formed by a cross-piece or stay 18 which carries a shock-absorbing cushion 19 formed of a piece of rubber tubing attached to a frame, for example.

Said cushion 19, at every printing movement, engages a roller 120 mounted on a rod 121 guided on the pedestal by a pin 122 in a slot 123; rod 121 thus raised causes a lever 106 pivoted on a pin 124 to oscillate, which lever carries a toothed sector 125 meshing with a wheel 126 loose on the paper wind-up reel pin 128.

Said wheel drives the reel through a ratchet gear and a friction clutch. The various members of said mechanism are so dimensioned that, at every oscillation of lever 106, the displacement of a point on the periphery of the paper reel 128 is greater than the forward step brought about by the driving mechanism of the strip, according to a known principle.

One peculiarity of this invention is that,

in order to avoid the noise produced by the driving mechanism of reel 128, namely by the ratchet gear, lever 106 may be moved on its support 98 so that the toothed sector 125 5 is no longer engaged with the toothed wheel 126. In proportion all the paper strip is advanced by the advancing mechanism, the printed part then falls freely by its own weight. In that way, the driving mechanism 10 of the reel 128 does not cause any noise at all.

In order that lever 106 may be made inoperative, same is provided with a slot 129 through which projects a pin 130 fixed to support 98 and carrying a small bell crank lever 131; one arm of the latter is provided with a roller 132 which engages lever 106 when the other arm of said bell crank lever is lowered so as to drive back sector 125 out 20 of engagement with wheel 126 as shown in chain lines in Figure 5. In Figure 5, support 98 is shown in raised position in order to reduce the dimensions of the drawings; the position which it really occupies on operation is shown in chain lines in 98^a.

When bell crank lever 131 is raised, lever 106 is brought back to its working position under the action of a spring 133.

The key levers operate type bars 20 with 30 which they are maintained in permanent contact by springs 21 housed in spring carriers maintained between partitions 2.

Said springs operate close to shaft 23 of 35 the type bars and have sufficient strength to maintain in position those of the type levers which are not in operation, whereas the other levers which are acted on by the fingers are brought back to their initial positions by the action of torsion springs 10 which act on 40 both arms of the universal bar 6 and the tension of which may be adjusted by hooking their ends in the various notches of racks 11 fixed to the supporting frame.

In addition, the printing block comprises 45 a pressure roller device comprising two sets of levers 24 and 25 carrying in sockets 26 and 26^a pins 27 and 28 the one of which 27 carrying three discs 27^a applies the paper in three bearing places against the printing cylinder, and the other 28 carries a soft or hard 50 rubber cylinder 28^a which applies the paper against the printing cylinder at the same time as it smooths it.

Both of said cylinders cause the adhesion 55 of the paper on the printing cylinder 81 with a pressure which depends on the strength of springs 29 and the paper is thus driven by the rotation of the printing cylinder after 60 every printing impact.

The pressure cylinders are positioned so 65 that their pressure on the printing cylinder 81 maintains same in permanent contact with the shaft whereabout it is made to rotate, and said contact always takes place along

one and the same generatrix of said shaft, even during the printing.

A stop 73 is provided in order to limit the upward stroke of the key levers (Figure 4); said stop consists of a reinforced rubber part 70 carried on two metal plates 74 and 75 the vertical position of which may be adjusted by means of a set screw.

Claims:

1. In a stenographic or similar machine 75 the combination of key levers each having two holes, a rocker mounted to tightly fit on each lever and having two arms which come into alignment with said holes in the lever for the vertical adjustment of said lever and a universal bar on which said rockers permanently rest.

2. In a device for regulating the position of the key levers in stenographic machines 80 relatively to the universal bar, the combination with each key lever of a shaft mounted on the said lever, a regulating or adjusting member fulcrumed on the said shaft and pressed upon one side of the lever so that it cannot be shifted except when a tight contact 85 is made, one of the ends of the said member being curved under the said key lever so as to cooperate with the said universal bar, the other end of the said regulating member being provided with two edges, the said key lever having two holes provided therein and so disposed to be partially covered by the two above mentioned edges of the regulating member, substantially as described and for 90 the purpose specified.

In testimony whereof I have hereunto affixed my signature.

MARC GRANDJEAN.
